DESIGN FOR HEAT-ABSORBING WATER CONDUIT FOR TANK WATER HEATERS

Clarence H. Morrow, Shaker Heights, Ohio, assignor to The Hotstream Heater Company, Cleveland, Ohio, a corporation of Ohio

Application May 5, 1942, Serial No. 106,796

Term of patent 14 years

To all whom it may concern:

Be it known that I, Clarence H. Morrow, a citizen of the United States and a resident of Shaker Heights, in the county of Cuyahoga and State of Ohio, have invented a new, original, and ornamental Design for a Heat-Absorbing Water Conduit for Tank Water Heaters, of which the following is a specification, reference being had to the accompanying drawing, forming a part thereof.

In said drawing, Fig. 1 is a side elevational

view of a heat-absorbing water conduit for tank water heaters showing my new design; Fig. 2 is a rear elevational view thereof; Fig. 3 is a front elevational view thereof; Fig. 4 is a top plan view thereof; Fig. 5 is a bottom plan view thereof; and Fig. 6 is a cross sectional view thereof on the line 6—6, Fig. 1.

I claim:

The ornamental design for a heat-absorbing water conduit for tank water heaters, as shown.

CLARENCE H. MORROW.
